(57) **CLAIM**

The ornamental design for a golf ball alignment device, as shown and described.

DESCRIPTION

FIG. 1 is an orthographic front view of a golf ball alignment device showing my new design which is in the form of a cap having a bill with a straight front edge. The straight front edge aids a golfer when putting to align the golf ball in a straight trajectory.

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a front elevational view thereof; and,

FIG. 7 is a back elevational view thereof.
